STARTER MOTOR CONTROL SYSTEM

Donn L. Dodge, Los Angeles, Calif.

Application October 19, 1949, Serial No. 122,290

4 Claims. (Cl. 290—38)

1

This invention relates to a starter motor control system. More particularly, it deals with a circuit to control the energizing of an electric starter motor for an internal combustion engine having an electric ignition system, which prevents energizing said starter motor while the internal combustion engine is running.

Previously, such circuits have been controlled either by the vacuum intake of the engine or the electric generator current developed by the running of the engine, or both, but none of these circuits to prevent energizing of the starter motor during the running of the engine have been reliable under all conditions of operation of the engine, such as when the vacuum in the intake substantially disappears when the engine is quickly accelerated, or when the generator current drops, and/or when a short or a break occurs in the control circuit itself.

Accordingly, it is an object of this invention to provide a simple, efficient, economic and completely effective control system for a starter motor for an internal combustion engine having an electric ignition system, such as employed in motor vehicles.

Another object of this invention is to provide such a control system which is reliable under all conditions of operation of the engine and which does not prevent energizing the starter motor to start the engine in the event of any failure in the control system itself.

In accordance with this invention, the electric starting motor system comprises two electric circuits, one for starting the motor which may be directly or indirectly connected, and the other for controlling or cutting off the first or starting motor circuit. The first circuit contains the conventional starter motor, current source such as a battery, and starter switch plus a normally closed cut-off switch. The other and second circuit for controlling the first and just mentioned starter motor circuit, contains the conventional ignition switch for the ignition system of the engine, plus a normally open switch closed by the vacuum from the intake of the engine when the engine starts, and a self-holding electromagnetic means such as relay or solenoid, which when energized by the closing of the vacuum switch, opens the normally closed cut-off switch in the first starter motor circuit, whereby the starter motor control circuit remains open until the other and second cut-off control circuit is broken by the opening of the ignition switch. Thus, if the engine stalls, it cannot be restarted until the ignition switch is closed and opened again. However, if any

2

failure occurs in the second cut-off control circuit, such as the burning out of the electromagnetic means or any other break in this circuit, a spring connected to the cut-off switch will close it in the first and starter motor circuit so that the starter motor can be operated in the normal and usual way as if the cut-off system of the invention were not employed.

The above mentioned and other features and 10 objects of this invention and the manner of attaining them will become more apparent and the invention itself will be best understood by reference to the following description of an embodiment of the invention taken in conjunction 15 with the accompanying drawing which is a schematic wiring diagram of the control circuits of the system of this invention.

Referring to the drawing, there is shown the conventional type of starter motor circuit for an 20 automobile internal combustion engine comprising a current source or storage battery 10 and a starter motor 11, connected through a heavy duty switch 12 by conductors 13 and 14. The switch 12 is closed only when the starter motor is to be 25 energized and may be closed manually by a push button, or indirectly by a starter relay 15 as shown, which is energized by a starter motor control circuit comprising the actuating coil 16 of the relay 15, conductors 17 and 18, and a starter 30 push button switch 20, which may be mounted on the dash board of the automobile. Also on or near the dash board may be mounted the ignition switch 25 which connects the battery 10 through conductors 26 and 27 to the ignition points of the engine. All of the above elements are common 35 to the electric starting and ignition systems of most automobiles.

The present invention consists of an additional 40 and second control circuit, shown inside of the dotted rectangle 30, which comprises a cut-off switch 35 inserted between the conductors 17 and 18 of the starter motor circuit, a vacuum operated switch 40 closed by the vacuum created in the intake manifold of the engine when the engine starts, and a self-holding electromagnetic means 45 such as a solenoid 50 to operate the cut-off switch 35 connected by a conductor 51. This second control circuit is energized through the ignition switch 25 and connecting conductor 52.

Each of the switches 12, 20 and 40 are shown 50 to be normally maintained open, insured by the action of compression springs 19, 21 and 41, respectively, and cut-off switch 35 is normally maintained closed, insured by the action of compression spring 36.

The vacuum operated switch 40 may comprise a movable contact 42 connected to a movable cork covered cap 43 which seals the end 44 of the tube 45, connected to the intake manifold of the engine, when a vacuum is created in the intake to produce a suction at 44. This movement of the cap 43 and its contact 42 closes the switch 40.

In order to start the internal combustion engine according to the system of this invention, first the electric ignition switch 25 is closed. At this time the starter switch 12 and starter control push-button switch 20 and vacuum operated switch 40 are open, and since the second control circuit 30 of this invention has not as yet been energized, the cut-off switch 35 is closed, all as shown in the drawing.

Next the manual starter button is pushed to close the switch 20. This energizes the starter relay 15 by a circuit from ground 22, through the contacts of switch 20, conductor 18, switch 35, conductor 17, coil 16, conductor 13, battery 10 and back to ground at 9. The energization of coil 16 operates the relay 15 to close the heavy duty switch 12 which closes the circuit from ground 9, through battery 10, conductor 13, switch 12, conductor 14, starter motor 11 and back to ground at 8, so that the starter motor is now energized and cranks the engine to start it.

When the engine starts, a vacuum is created in the intake manifold to cause a sufficient suction at 44 to close the cap 43 and switch 40. This closes the second control circuit 30 from ground 46 through switch 40, conductor 51, solenoid 50, conductor 52, ignition switch 25, conductor 26, battery 10 and back to ground at 9. This second cut-off control circuit energizes the electromagnetic means 50 to open the cut-off switch 35 and close its self-holding contacts 53 and 54, which may be with the electrically isolated conducting bridge 55 of the switch 35, or by a separate conducting bridge means. The opening of the switch 35 breaks the starter control circuit which in turn breaks the heavy duty starter motor circuit by opening heavy duty switch 12, and stops the starter motor whether switch 20 is still held closed or not, as well as preventing the switch 20 from later closing the starter motor circuit as long as the engine ignition circuit is energized and the switch 35 is held open by the energized electromagnetic means 50. The holding circuit for the electromagnetic means is through now-closed contacts 53 and 54 to ground 56, in parallel with or short circuiting the circuit to ground 46 through the vacuum operated switch 40. Therefore, regardless whether or not the vacuum operated switch may open due to rapid acceleration of the engine, such opening will not permit the closing of the starter motor circuit by the closing of cut-out switch 35.

In order to stop the engine, the ignition switch 25 must be opened, which breaks the second control circuit 30 and permits the conducting bridge 55 to again close the switch 35 due to the action of the spring 36. The stopping of the engine then permits the vacuum operated switch 40 to open, insured by the action of the spring 41, and the starter button switch 20 is again connected in the starter motor control circuit so that the engine may again be started as described above.

If the engine stalls, dies, or stops while the ignition is still on, the circuit 30 remains energized and the switch 35 remains open so that the ignition must be turned off, or the ignition switch 25 opened, and then turned on or closed again, before the engine can be started in accordance

with the operation of the circuits described above. Such an additional cutting of the ignition each time before the engine can be started, insures that the starter motor can never be energized during the operation of the motor regardless of how weak the vacuum on the intake manifold becomes.

Furthermore, if any part of the circuit 30 fails or burns out, the engine can always be started in the regular manner because the spring 36, then closes the switch 35 so that the known conventional elements of the starter motor circuit may be used in the conventional way, the only disadvantage being that the cut-off switch no longer insures the cut-off of the starter motor while the engine is running.

Although the above embodiment has been described for an indirect type of starter motor control circuit containing a starter motor relay 15, the same principle of this invention may be applied to such a circuit directly in which the switch 12 is replaced by the manual push button switch 20 and the normally closed cut-off switch 35. The reason that the starter motor energy supply circuit from battery 10 through switch 12 to the starter motor 11 is preferably made separate from the push button circuit, is because that the amount of current required for the motor 11 is so great that it requires very heavy conductors, and switch contacts. Accordingly, the fewer number of such heavy switches and the less amount of such heavy conductors employed, the more economical and simpler the installation becomes.

Another advantage of the present invention is that it can be installed easily into any existing starter motor control system without changing any of the existing conductors. All that need to be inserted are the contacts of normally closed cut-off switch 35 in the starter motor control circuit, and the only other additional equipment which needs to be installed is the vacuum operated switch 40 and the electromagnetic means 50, which are connected to terminals or contacts existing already in the control system.

While there is described above the principles of this invention in connection with specific apparatus, it is to be clearly understood that this description is made only by way of example and not as a limitation to the scope of this invention.

What is claimed is:

1. An electric starter motor circuit for an engine having an electric ignition system which engine produces a vacuum, comprising a starter motor circuit containing a starter motor, a normally open starter switch and a normally closed cut-off switch; and a control circuit for said starter motor circuit containing the ignition switch of said engine, a vacuum closed switch, a solenoid to open said normally closed switch to break said starter motor circuit, and means to maintain said solenoid energized as long as said ignition switch is closed.

2. The system of claim 1 wherein said means to maintain said solenoid energized comprises a pair of self-holding contacts in the energizing circuit of said electromagnetic means.

3. The system of claim 2 wherein said pair of self-holding contacts are in electric parallel to the contacts of said vacuum operated switch.

4. In a starter motor circuit for an internal combustion engine having an electric starter motor, an intake manifold, a starter switch, an electric ignition switch and an electric current source, the improvement comprising a normally

closed cut-off switch in said starter motor circuit, means responsive to vacuum in said intake manifold when said engine starts to close a vacuum operated switch, a second circuit containing said vacuum operated switch, said ignition switch and means to open said normally closed cut-off switch when said vacuum operated switch is closed, and means to maintain said normally closed cut-off switch open thereafter as long as said ignition switch is closed.
